JOSEPH O. QUERY, OF SOMERVILLE, MASSACHUSETTS.

APPARATUS FOR CONTROLLING RAILWAY-TRAINS.

1,157,723.

Specification of Letters Patent.

Patented Oct. 26, 1915.

Application filed November 10, 1913. Serial No. 800,075.

To all whom it may concern:

Be it known that I, JOSEPH O. QUERY, a citizen of the United States, residing at Somerville, in the county of Middlesex and 5 State of Massachusetts, have invented new and useful Improvements in Apparatus for Controlling Railway-Trains, of which the following is a specification.

This invention relates to improvements in 10 apparatus for controlling railway trains or vehicles and has for its object to provide a device which is adapted to reduce the speed of a train traveling at or greater than a predetermined rate of speed, or to entirely 15 stop said train, said device being arranged to coöperate with a signal in accomplishing the results desired.

The invention consists in the combination and arrangement of parts whereby the 20 above objects and certain other objects hereinafter appearing may be attained, as set forth in the following specification and particularly pointed out in the claims.

Referring to the drawings: Figure 1 is a 25 diagrammatic view of a device embodying my invention. Fig. 2 is a sectional elevation taken on line 2—2 of Fig. 1 viewed in the direction of the arrows on said line. Fig. 3 is a sectional elevation taken on line 30 3—3 of Fig. 1. Figs. 4, 5 and 6 inclusive are diagrammatic views of the trip device illustrating several positions of the various parts of which said device is composed. Fig. 7 is a detail sectional view of the valve 35 35. Fig. 8 is a detail transverse section taken on the line 8—8 of Fig. 1.

Like numerals refer to like parts throughout the several views of the drawings.

In the drawings, 8 represents a brake 40 mechanism of the usual automatic air brake type, only portions of which are illustrated in the drawings, said portions consisting of a train pipe 9, engineer's valve 10 and equalizing reservoir 11 all of which are connected together in the usual manner. An air reservoir 12 is connected with said train pipe and said equalizing reservoir through the engineer's valve 10 by means of pipes 13 and 14, while interposed between said 45 reservoir and said engineer's valve or said train pipe and connected by said pipes 13 and 14 is an air supply valve 15, preferably arranged to reciprocate in a casing 16 to which are connected the pipes 13 and 14,

said pipes adapted to be connected or disconnected by the reciprocations of said valve within said casing. A discharge valve 17 is also provided for said brake mechanism preferably in the end of a cylinder 18 connected by a pipe to the equalizing reservoir 50 11, said reservoir being connected by a pipe 20 to the engineer's valve 10. The pipe 19 enters the end of the cylinder 18 through a chamber 21 which incloses one side of the valve 17.

A piston 22 is arranged to reciprocate within the cylinder 18, said piston being connected by a piston rod 23 to the valve 15 and during certain times in the operation of the device air is admitted into the chamber 24 of the casing 16 against the piston 22, whereupon said piston will be moved toward the left, Fig. 1, and during a portion of its movement a stem 25 of the valve 17 will be engaged by said piston to move said 70 valve which is normally retained in its closed position by a spring 26. On the movement of said valve 17 from its seat the air within the chamber 21 and the reservoir 11 will immediately pass beneath said valve 80 and into the cylinder 18 from whence said air is permitted to escape through an opening 27. The escape or discharge of the air from the equalizing cylinder sets the brakes of the train in a manner well known to those 85 skilled in the art and requiring no further amplification.

By the arrangement of the valve 15 relatively to the piston 22 it will be seen that the first part of the movement of said piston 90 will cause the valve 15 to cover the ends of the pipes 13 and 14 which enter the casing 16, thus cutting off the supply of air from the reservoir 12 to the brake mechanism. On the continued movement of said piston 95 however a gap which exists between the end of the stem 25 on the valve 17 and the piston 22 will be closed and said valve 17 opened without any waste of air from said main reservoir.

All of the mechanism hereinbefore described is carried by the train which is adapted to move along the line of way or track 28. Means are also carried by said train which are adapted to be acted upon to 105 close said valve 15 and open the valve 17 whereby the brakes on the train may be applied, said means being so arranged that

they will be rendered operative only when said train is traveling at a predetermined rate of speed and under abnormal conditions, such for instance, as the setting of a signal at danger. To accomplish this purpose a cylinder 29 is provided which is pivoted to a suitable frame 30 permitting said cylinder to be rocked transversely of said train, the normal position however of said cylinder being vertical, as illustrated in Fig. 2. A piston 31 is arranged to reciprocate in said cylinder and is provided with a piston rod 32 depending therefrom and projecting from the lower end of said cylinder. Secured to the upper end of the cylinder 29 is a pipe 33 which preferably connects said cylinder with the air reservoir 12, a flexible connection 34 being provided in said pipe to permit said cylinder to be rocked. A valve 35, preferably of the rotary type, is arranged in said pipe 33 and adapted to be operated when the train is traveling at a predetermined rate of speed to permit air to pass through a passage 35' in the rotary member 35² of said valve through the pipe 33 into the cylinder 29.

A lever 36 is secured to the valve 35 and is adapted to engage at its free end a grooved collar 37 adjustably arranged upon a sleeve 38 constituting the movable member of a governor 39, said sleeve being connected by links 40 to centrifugal weights 41, said weights being pivotally connected to a collar 42 fast to a shaft 43, said shaft in turn being geared to a movable part of the train, preferably one of the axes 44. Said governor and valve constitute the means adapted to effect the movement of said piston when said train is traveling at a predetermined speed. As the air is admitted to the cylinder 29 through the pipe 33 the piston 31 will be forced downwardly therein carrying with it a depending trip finger 45 pivoted at 47 to the lower end of the piston rod 32 and with said trip finger in its lowermost position, an obstacle 46 arranged at a predetermined point along the line of way will engage said finger and rock the same upon its pivot 47. An arm 48 on said trip finger when in its lowermost position is arranged to engage a stop 49 adjacent the lower end of a rod 50, said rod being connected to a slide valve 51 which is arranged to slide within the cylinder 29 out of the range of the piston 31. A pocket 52 is provided in the valve 51 which is long enough to extend across the ends of two out of three pipes 53, 54 and 55 which are connected with the cylinder 29. The pipe 53 is merely an exhaust pipe opening to the atmosphere. The pipe 54 is connected by a flexible pipe 56 to a pipe 57 which extends to and is connected with the casing 16, while the pipe 55 extends to the air reservoir 12, this pipe also being provided with a flexible connecting

pipe 58 to a pipe 59 extending to the air reservoir 12.

Under normal conditions with the train at rest or traveling along the track at a speed less than that determined by the governor 39, the valve 51 will remain with its pocket 52 across the ends of the pipes 53 and 54 leaving the chamber 24 in the casing 16 open to the atmosphere and the pipe 55 closed, but when the speed of said train reaches said predetermined speed or beyond, the lever 36 is moved by said governor to move the rotary member 35² to align the passage 35' with the pipe 33, thus opening said valve 35 and permitting the air to enter the cylinder 29 to move the piston 31 downwardly from the position illustrated in Fig. 1 to that illustrated in Fig. 4 and moving the arm 48 into contact with the stop 49 on the rod 50. Said movement of the piston 31 compresses a spring 60 encircling the piston rod 32. During said downward movement of said piston 31 the trip finger 45 is carried into the path of the obstacle 46 and as said train approaches said obstacle said finger is rocked upon its pivot 47 to the position illustrated in Fig. 6, said rocking movement of said finger being sufficient to move the valve 51 by means of the rod 50 and stop 49 downwardly to the position illustrated in Fig. 6 with the pocket 52 extending across the ends of the pipes 54 and 55, permitting air to enter through said pipe 55 from the air reservoir 12 into said pocket 52 and the chamber 52' above said valve through openings 52² in said valve, see Fig. 8, thence outwardly through the pipe 54 to the chamber 24 thereby moving the piston 22 in the cylinder 18 toward the left as hereinbefore described.

The downward movement of the valve 51 and rod 50 serves to compress a spring 61 encircling said rod 50 and engaging a foot 62 fast to the casing 29. Resulting from the movement of said piston 22 toward the left Fig. 1, the valve 15 is closed, while the valve 17 is opened and the air from the equalizing reservoir is released, thus applying the brakes and reducing the speed of the train which also reduces the speed of the governor 39 causing the collar 37 to drop thereby closing the valve 35 by moving the passage 35' out of alignment with the pipes 33. The rotary member 35² however of said valve is rotated sufficiently to align the passage 35' with an exhaust port 63, while an arm 64 of the passage 35 aligns with the portion of the pipe 33 leading to the cylinder 29, thus permitting the air within said cylinder to escape whereupon the spring 60 will cause said piston 31 to move upwardly to its normal position.

During the latter movement of the piston 31 the trip finger 45 is returned to its normal position by a stop rod 65 which engages a

105

110

115

120

125

130

projection 66 on said trip finger 45. The movement of said trip finger however has no effect upon the rod 50, which at this time is retained in its lowermost position by the pressure of the air from the air reservoir through the pipe 55 into the pocket 52, chamber 52' and openings 52² against the lower surface 67 thereof, said pressure overcoming the pressure of the spring 61. With the valve 51 in this position the train will be brought to a standstill and remain in such a position until the pressure of the air against the surface 67 is removed, which may be accomplished by opening a valve 69 in the casing 16 and permitting the air entering said casing through the pipe 54 to escape, thus lowering the pressure in the chamber 52' and permitting the spring 61 to force said valve to its normal position.

The means hereinbefore described are for the purpose of closing the valve 15 and turning the valve 17 to apply the brakes to the train when said train is traveling at a predetermined speed, said mechanism being operated by obstacles 46 which may be arranged at predetermined points along the line of way. It is very often necessary that the speed of the train be reduced along certain portions of the track but not brought to a standstill and for this purpose means are provided to close said discharge valve 17 and open said air supply valve 15 whereby the brakes may be automatically released in the usual manner. Included in said means is a supplementary trip finger 70, substantially shorter than the finger 45 and pivoted at the front thereof preferably at 71 to an arm of the trip finger 45 and normally depending therefrom substantially parallel with the finger 45 but being shorter than the trip finger 45 and at the front thereof it is prevented from engaging the obstacle 46. An arm 72 formed on said finger is adapted to encircle a rod 73 and when rocked about the pivot 71 to engage a stop 74 on said rod 73. A second obstacle 75 is arranged adjacent the obstacle 46 within the section of the track where it is desired to merely slow down the train rather than stop it and when the trip finger 45 is rocked by its obstacle 46 into the position indicated in Fig. 6 said trip finger 70 being pivoted thereon will be moved thereby into a position to be engaged by said obstacle 75. Upon the rocking of said supplementary trip finger 70, a lever 76 which is operatively connected with said supplementary trip lever by the link 78 will be rocked upon its pivot 77 and an arm 78 thereof will engage a pin 79 which will be moved by said engagement from the position indicated in Fig. 4 to that shown in Fig. 6. The lever 76 and said pin are mounted to move with the piston 31 and with a guide 80 which constitutes a bearing for the valve 51.

The pin 79 is adapted to be moved from a position without to a position within the path of said valve 51, the normal position thereof being without said path, as shown in Fig. 4, which is the position occupied by said pin when the mechanism is operated to stop the train. When it is desired to reduce the speed of the train instead of stopping the same, the finger 45 contacts with the obstacle 46 and is thereby rocked upon its pivot 47 from a vertical position, as indicated in Fig. 4, to an inclined position, as indicated in Fig. 6, which movement reciprocates the valve 51 to admit air to the cylinder 16 thereby applying the brakes in the manner hereinbefore described. By the rocking of the finger 45, as stated, the finger 70 will be lowered from the position indicated in Fig. 4 to the dotted position indicated in Fig. 6, or in a position to contact with the obstacle 75, which is placed adjacent to the obstacle 46, as hereinbefore stated, but close enough to operate said finger 70 and rock the same from its dotted line position Fig. 6 to the full line position thereof before the finger 45 has had an opportunity to return to its normal position, as in Fig. 4. The movement of the finger 70 just described causes the pin 79 to be moved in its bearings, as hereinbefore stated, to the position shown in Fig. 6 where it will engage the under face of said valve 51 when the piston 31, which carries said pin, is moved upwardly upon the exhausting of the air within the cylinder 29, said air being exhausted at this time by means of the governor 39 whose speed is reduced simultaneously with a reduction in speed of the train. With the pin 79 in the position stated it will be evident that said valve 51 will be engaged thereby and moved upwardly to interrupt the connection between the pipes 54 and 55, thus shutting off the supply of air from the tank 12 to the cylinder 16, returning all of the parts to their normal positions, as indicated in Fig. 5, without requiring the services of the operator.

A projection 81 is provided on the under face of the valve 51 which engages the head of the pin 79 and retains said pin in its projected state until the piston is again lowered after which said pin returns to its normal position out of the path of said valve. Means are provided for retaining the pin in its projected relation to the guide 80 until said pin has engaged said valve 51, said means preferably consisting of a weight 82, said weight being secured to the lever 76 and adapted to be swung to an inclined position upon one side or the other of a vertical plane containing the axis of the pivot 77. With the trip fingers 45 and 70 in the positions illustrated in Fig. 6 it will be seen that said weight will cause the arm 78 to remain in engagement with the pin 79. This

position however is maintained until the piston is retracted and the pin 79 engages the projection 81, but upon the returning of said fingers to their suspended positions, as illustrated in Fig. 5, said weight 82 will be thrown to the opposite side of said central plane and the arm 78 thereof removed from the pin 79 leaving said pin suspended by the projection 81, said lever 76 being in a position to be operated during the next successive operation of the piston 31.

If desired the apparatus hereinbefore described may be used in connection with a signal system, which may be of the usual block type system and warns the engineer to stop his train, providing there is a train within the block toward which his train is approaching, said apparatus being so arranged that said engineer, may if desired, apply the brakes by operating the lever of the engineer's valve 10 to discharge the air from the equalizing reservoir independent of said apparatus, but should said engineer fail to observe that the signal is set at danger, said device will be automatically operated to apply said brakes. Should the signal be set at safety there would be no need of applying the brakes to the train should said train be traveling at the predetermined rate of speed. With the mechanism hereinbefore described it would be impossible for the train to go by said signal or the tripper 46 without applying said brakes, but means are provided which are rendered operative by the setting of said signal at safety adapted to move said trip fingers out of the path of the obstacles 46 and 75, thus permitting said train to pass the signal without the slightest reduction in the speed thereof. In the carrying out of this portion of the invention the cylinder 29 is preferably pivotally mounted upon the frame 30 and connected by a link 83 to one arm of a bell crank lever 84 pivoted upon a stationary member 84' of the train, see Fig. 2. The other arm of the lever 84 is connected by a link 85 to the armature of a solenoid 86 which is energized at the proper time in the operation of the device to rock said cylinder 29 into the position illustrated in dotted lines, Fig. 2.

When the cylinder 29 is in its vertical position the center of the pin 87, which connects the link 83 with the lever 84, is substantially below a plane containing the axis of the pivot 88 of said lever and the axis of the pin 89 connecting said link 83 with said cylinder. The end of the link 83 containing said pin 87 is supported by the frame 84' by which arrangement the cylinder 29 is locked in its vertical position, said locking being further assisted by a projection 90 formed on the link 83 and adapted to engage the edge of the frame 84'.

15 The solenoid 86 is connected by wires 91

and 92 with shoes 93 and 94 which may also be carried by the train and adapted to engage contacts 95 and 96 which are arranged at a proper distance from the obstacle 46. The contacts 95 and 96 are connected in circuit with a series of batteries 97 by wires 98 and 99 which are also connected to a switch 100. The switch 100 is operatively connected preferably by a rod 101 to a signal arm 102 which is mounted upon a suitable post 103 arranged adjacent to the track 28.

With the signal arm 102 in the position illustrated in Fig. 1, which is the danger position, the switch 101 will be opened thus preventing the shoes 93 and 94 during their contacting with the contacts 95 and 96 respectively from energizing the solenoid 86 to move the trip fingers 45 and 70 out of the paths of the obstacles 46 and 75. This results in the reducing of the speed of the train providing the obstacle 75 is placed adjacent the tripper 46, but without said tripper 75 the train will be brought to a stop.

Upon the movement of the signal arm 102 from its full line position indicating an abnormal condition to its dotted position, see Fig. 1, the switch 100 will be moved to connect the contacts 100' and 100'' of the circuit containing the wires 98 and 99 and battery 97 and when the shoes 93 and 94 engage the contacts 95 and 96, said circuit will be entirely closed and the solenoid 86 energized whereby said cylinder 29 will be rocked upon its pivots and the trip fingers 45 moved out of the paths of the obstacles.

100 In the foregoing description the operations of the various devices of the apparatus have been fully described and therefore it is believed no further description is necessary. Furthermore in this description one specific embodiment of my invention has been disclosed for the purpose of illustration, but it is to be understood that the invention is not limited to the specific details shown and that many modifications may be made in the construction and arrangement of certain of the parts without departing from the spirit and scope of the invention as set forth in the appended claims.

115 Having thus described my invention what I claim and desire by Letters Patent to secure is;

1. In a train controlling apparatus the combination of an air supply valve, an air discharge valve, a stationary obstacle, means carried by said train adapted to be moved by the traveling of said train at a predetermined speed into a position to be acted upon by said obstacle to close one and open the other of said valves, a signal, and means rendered operative by the setting of said signal at safety adapted to move said valve opening and closing means out of the path of said obstacle.

120 2. In a train controlling apparatus the

- combination of an air supply valve, an air discharge valve, an obstacle, a cylinder carried by said train, a piston adapted to be reciprocated in said cylinder, a governor carried by said train adapted to affect the reciprocations of said piston, a trip finger carried by said piston adapted to be moved thereby to engage said obstacle, means operated by the tripping of said finger adapted to close said supply valve and open said discharge valve, a second obstacle arranged adjacent said first named obstacle, a supplementary trip finger adapted to be moved by the tripping of said first named finger into a position to engage said second named obstacle, and means rendered operative by the tripping of said supplementary trip finger adapted to effect the opening of said air supply valve and the closing of said discharge valve.
3. In a train controlling apparatus the combination of a train pipe, a cylinder pivotally mounted to rock transversely of said train, a piston adapted to be reciprocated in said cylinder, a pair of obstacles arranged along the path of said train, a trip finger carried by said piston adapted to be moved during the reciprocations of said piston into the path of one of said obstacles, a second trip finger carried by said first finger and adapted to be moved by the operation of said first named finger into the path of the other obstacle, instrumentalities rendered operative by the tripping of said finger adapted to affect the admittance of air to and the discharge of air from said train pipe, a signal and means rendered operative by the setting of said signal at safety adapted to rock said cylinder transversely of said train to move said trip fingers out of the path of said obstacles.
4. In a train controlling apparatus the combination of a brake mechanism, a trip device carried by said train, an obstacle arranged in the path of said train, means rendered operative by the movement of said train at a predetermined speed adapted to move said trip device into a position to engage said obstacle to operate said brake mechanism and apply the brakes, a second obstacle, and means rendered operative by the engagement of said trip device with said second obstacle adapted to release said brakes.
5. In a train controlling apparatus the combination of a line of way along which said train is adapted to be moved, a brake mechanism for said train, a trip device for said brake mechanism pivotally arranged on said train to move transversely of said line of way into and out of its operative positions, electrical instrumentalities adapted to rock said trip device, a signal, a pair of electric circuit terminals connected in circuit with said electrical instrumentalities,

and means operated by the movement of said signal from one position to another adapted to connect said electric circuit terminals.

6. In a train controlling device the combination of a line of way along which said train is adapted to move, a stationary obstacle, a brake mechanism for said train, a trip device carried by said train adapted to be moved to engage said obstacle when said train is moving at a predetermined rate of speed, a signal adjacent said line of way, and means carried by said train and rendered operative and inoperative by the movements of said signal to move the trip device to a position where it will not engage the obstacle or to permit said trip device to engage said obstacle and operate said brake mechanism.

7. In a train controlling apparatus the combination of a line of way along which said train is adapted to be moved, a signal, a brake mechanism carried by said train, a trip device adapted to be operated to effect the operation of said brake mechanism, an obstacle adapted to engage said trip device, an electric circuit including a pair of terminals adapted to be connected by the setting of said signal at safety, a pair of contacts also included in said electric circuit, a solenoid carried by said train, means on said train adapted to engage said contacts to connect said solenoid with said electric circuit whereby said solenoid may be energized, and means rendered operative by the energizing of said solenoid adapted to move said trip device out of the path of said obstacle whereby said brake mechanism will not be operated.

8. In combination a line of way, a vehicle arranged to travel along said line of way, an obstacle on said line of way, a trip device pivotally mounted on said vehicle and normally arranged in alignment with said obstacle, an arm pivoted on said vehicle, a link pivotally attached at one end to said trip device and at its opposite end to said arm, the axis of said last mentioned connection lying below a plane containing the axis for said arm and the pivot on said trip device, a stop adapted to limit the downward movements of said arm and said link, and electrical instrumentalities adapted to move said arm upwardly and rock said trip device into position out of alignment with said obstacle.

9. A train controlling device having, in combination, a train pipe, a discharge valve therefor, a supply valve for said train pipe, a cylinder, a piston arranged to reciprocate in said cylinder, said piston being operatively connected with said discharge valve and said supply valve, a third valve adapted to supply fluid to said cylinder, a trip device pivotally arranged on said train, an obstacle adapted to be engaged by said trip device to operate said third valve, electrical

instrumentalities adapted to rock said trip device, and a pair of contact plates arranged at a predetermined distance from said obstacle adapted under predetermined conditions to render said electrical instrumentalities operative.

In testimony whereof I have hereunto set

my hand in presence of two subscribing witnesses.
